UNITED STATES PATENT OFFICE.

SAMUEL J. WAKEFIELD, OF ABBEVILLE, SOUTH CAROLINA.

COTTON-GIN.

1,266,643.

Specification of Letters Patent. Patented May 21, 1918.

Application filed January 25, 1917. Serial No. 144,437.

To all whom it may concern:

Be it known that I, SAMUEL J. WAKEFIELD, a citizen of the United States, and resident of Abbeville, county of Abbeville, State of 5 South Carolina, have invented certain new and useful Improvements in Cotton - Gins, of which the following is a specification.

This invention relates to cotton gins of the type which is adapted to act on the cotton 10 as it comes from the field without previous ginning and has particular reference to means for properly presenting the cotton to the saws of the gin after it has been fed into the breast of the gin above the saws. It consists in means for maintaining a uniform rotating roll of cotton in the breast of the gin 15 and for positively rotating such roll at that speed which will enable the saws to act in removing the lint from the seed most effectively, rapidly and with the least possible cutting or tearing of the fiber of the cotton. It embodies the use of an impeller in the breast of the gin and means for positively turning it at the desired speed whereby the 20 roll of cotton carried and impelled thereby will so reach the saws as to secure the best results. The novel features of my invention 25 will be apparent from the following description taken in connection with the drawings.

30 In the drawings,

Figure 1 is a cross section through the breast of the gin showing my invention applied thereto;

35 Fig. 2 is a vertical section on the line 2-2 of Fig. 1.

Fig. 3 is a front elevation of a machine embodying the invention showing the means for driving the parts; and

40 Fig. 4 is an end elevation showing the driving means.

I am aware that impellers have been used in the breasts of machines used for delinting cotton seed which has previously been ginned and that impellers have been proposed in 45 treating motes and trash having some lint adhering to them but I do not believe that impellers have been used in the breasts of gins adapted and intended to gin cotton in its natural condition as it comes from the 50 field. In the case of previously ginned seed which is to be delinted and in the case of motes and trash there is very little fiber compared to the size and weight of the mass and

it is so short that the saw teeth cannot get sufficient hold on it to exert any real pull in 55 the direction of turning the roll of material. In that case, therefore, the movement of the saw teeth will not be sufficient to turn the roll in order to present other parts of the mass to the action of the saws and it is necessary to have positive means for rotating the 60 roll so that the saws may do their work. In the case of cotton in its normal condition, however, the fiber is so long and thick that the saw teeth may get a good hold on the 65 roll to turn it and the thick interlocking fiber makes the entire roll rotate under the influence of the saws engaging the surface at one point. It has not only not been considered necessary to positively rotate the roll 70 in ginning ordinary cotton but on the contrary if the suggestion were made to a cotton ginner of doing so it would strike him naturally and spontaneously that the idea was a foolish one and would prevent proper 75 ginning. It has always been assumed that the roll of cotton should resist the turning movement which the saws tend to impart so as to give the resistance necessary to enable the saws to cut or tear the lint from the 80 seed in the roll and the ginner would regard it as more reasonable to retard the rotation of the roll rather than to accelerate it. I have discovered, however, that the use of an impeller for turning the roll at a greater 85 speed than that at which the saws would turn it accomplishes very remarkable results not only in improving the character of the lint produced but in increasing the speed at which the cotton can be ginned. I find that 90 the fiber of the lint taken off by the saws is much better and longer, not being torn or cut and this adds greatly to its value. I find further that a single gin can delint about twice as much cotton in a given time 95 where the roll is positively turned, according to my invention, than where the saws turn the roll.

My invention involves not merely the use of an impeller for turning and controlling 100 the roll of cotton but the particular arrangement of the impeller in the breast with reference to the saws. I find that the location of the impeller in the breast makes a remarkable difference in the operation and 105 that the best results are secured when it is

not located in the center but nearer to the saws than to the front of the breast as shown in Fig. 1. With the impeller located near the saws the result is that the side of the roll of cotton next to the saws is in a sense compressed and is thus presented to the saws in compact condition. This seems to enable the saws to do their work with greater ease and more efficiently. Whatever the reason may be I have found it to be a fact that this location of the impeller produces remarkably improved results. It will be noted from the arrangement shown in the drawing that the roll of cotton will be compressed at that part where it leaves the saws after the saws have cut into it. I find that this compression of the roll next to the saws does not tend to break the roll but that on the contrary the use of the impeller prevents the breaking of the roll.

I find that in the ordinary operation of a gin where the saws make 400 revolutions per minute, the roll turned by those saws makes about 60 or 70 revolutions per minute. Several inches of the periphery of the saw blades project into the roll of cotton and I believe that the first of the teeth in the projecting portion catch and remove the available lint and that the succeeding teeth striking the adjacent mass do nothing except harm and that they tend to break and tear the lint. That lint which is caught by a tooth is carried through a greater mass of cotton in the roll than would be the case if the roll were positively turned and the lint is therefore injured by such contact with the mass. According to my invention, the saws need not enter the roll of cotton so far as is customary in the gins where the saws turn the roll and this further serves to lessen the strain on the lint and to decrease cutting and tearing it. In actual operation I find it advantageous to gear or connect my impeller in such way that the roll of cotton will turn at a speed somewhat less than one-half the speed of the saws.

In the accompanying drawings I have illustrated one embodiment of my invention but it will be understood that the idea is applicable to various types of gins which are now in use and in which the saw teeth now turn the roll of cotton. In the drawings I have shown diagrammatically the casing or main frame 10 of a gin and embodied in it I have shown the saw cylinder 11 and the usual brush cylinder 12. The periphery of the saws projects through the vertical ribs 13 into the open space 14 in the breast of the gin. 15 represents the front wall of the breast of the gin and it will be understood that the breast is pivoted or hinged at the top so that it can be raised in the usual way to furnish access to the saws. Cotton as it comes from the field is fed into the breast of the gin through the openings 16 at the top

by any suitable feeding means. The ginned seed falls through the opening 17 at the bottom of the breast and may be collected and carried away by any suitable means.

My impeller embodies an impeller shaft 18 extending longitudinally within the breast of the gin parallel to the periphery of the saws and is mounted in suitable bearings at the ends of the breast. This shaft has projecting from it any suitable blades 19 for engaging and turning the roll of cotton. These blades preferably project to a point within about an inch of the periphery of the saw cylinder. The shaft 18 is rotated positively by any suitable means but preferably from the main shaft which serves to drive the saws and other parts of the gin. In Fig. 2 I have shown a pulley 20 on the end of the shaft 18 which may be driven by a belt or chain connection from the shaft above mentioned. As above stated the belt, gear or other drive connections will preferably be so arranged as to give the impeller shaft a speed about half of that of the saw cylinder. In Figs. 3 and 4 I have shown one arrangement by which the saw cylinder and the impeller may be driven at the proper relative speeds as above indicated. The main shaft 25 shown in these figures is, of course, driven from any suitable source of power. The wheel or pulley 26 on this main shaft drives the saw cylinder shaft 27 through pulley 28 on the end thereof by means of the belt or chain 29. The relative speed at which the saw cylinder is rotated is determined by the relative sizes of the pulleys 26 and 28. The main shaft 25 also drives the counter shaft 30 through pulleys 31 and 32 and the connecting chain or belt 33 and in this instance the pulley 32 on the counter shaft is preferably made of larger diameter than the pulley 31 on the main shaft so that the counter shaft rotates at a less speed than the main shaft. The counter shaft 30 is provided with a pulley 34 which through the belt or chain 35 drives the impeller shaft 18 through pulley 36. The belt 35 may be kept taut by a belt tightener or any suitable construction, that shown, consisting of the roller 37 mounted between the ends of the hinged arms 38. With the driving connection of the kind indicated it will of course be understood that the impeller shaft and saw cylinder shaft may be given the desired relative speeds by properly proportioning the sizes of the pulleys 26, 28, 31, 32, 34 and 36. I also find that it is of advantage to place at the ends of the shaft 18 within the breast of the gin disks 21, 22 which are secured to and rotate with the shaft and these disks may be mounted in circular recesses in the end plates 23, 24 of the breast of the gin. Since these disks rotate with and at the same speed as the shaft they avoid any friction at the ends of the roll of cotton against the end plates 130

of the breast. This tends to maintain the roll of cotton in proper uniform shape and to lessen the power required in driving the machine. I further find that my impeller 5 as a whole tends to maintain the roll of cotton in proper shape and to prevent that breaking or bulging up of the roll which is quite common in the case of gins where the saws drive the roll.

10 I find that by the use of my impeller the roll will be maintained in proper shape and will not break no matter how much or how little cotton is fed to it and that the seed will be ginned cleaner than if no impeller is used.

15 There will furthermore be no loss of seed and the operator does not have to raise the breast of the gin in order to change from one bale of cotton to another. Frost bitten cotton and damp cotton, which is hard to 20 gin where the saws turn the roll, can be ginned as rapidly and easily in my device as good dry cotton can be ginned in the ordinary gin. Another very important feature about my invention is that it prevents the 25 cotton from accumulating and getting packed between the ribs where the saws pass. This packing of the cotton against the sides of the saws where they go through the ribs causes such friction against the saws as to 30 sometimes set the cotton on fire. By my construction there is no such friction and no such danger of fire.

Having thus described the invention what is claimed and desired to be secured by 35 Letters Patent is:

1. In a cotton gin adapted to operate upon previously unginned cotton the combination with a saw cylinder, of ribs through which the saws project, a roll box in front of said 40 ribs to receive the cotton to be ginned, a rotary impeller in said roll box adapted to turn the roll of cotton therein with substantial uniformity throughout its length bringing successive peripheral portions of the 45 cotton roll in contact with the projecting portions of the saws and means for positively rotating said saw cylinder and impeller at different speeds the driving connections being such as to rotate the impeller at 50 a speed less than the speed of the saws but greater than the speed at which a normal roll of cotton would be rotated by the engagement of the saws.

2. In a cotton gin adapted to operate upon 55 previously unginned cotton, the combination with a saw cylinder, of ribs through which the saws project, a roll box in front of said ribs to receive the cotton to be ginned, a rotary impeller shaft in the roll box provided with blades extending therefrom 60 adapted to reach nearly to the periphery of the saws adapted to turn the roll of cotton therein bringing successive portions of the cotton roll in contact with the projecting 65 portions of the saws and means for posi-

tively rotating said saw cylinder and impeller at different speeds the driving connections being such as to rotate the impeller at a speed less than the speed of the saws but greater than the speed at which a normal 70 roll of cotton would be rotated by the engagement of the saws.

3. In a cotton gin adapted to operate upon previously unginned cotton, the combination with a saw cylinder, of ribs through which 75 the saws project, a roll box in front of said ribs to receive the cotton to be ginned, a rotary impeller in said roll box adapted to turn the roll of cotton therein uniformly from end to end bringing successive portions 80 of the cotton roll in contact with the projecting portions of the saws, circular disks secured to and turning with said impeller at the ends of said roll box, and means for positively rotating said saw cylinder and impeller at different speeds the driving connections being such as to rotate the impeller at a speed less than the speed of the saws but greater than the speed at which a normal 85 roll of cotton would be rotated by the engagement of the saws.

4. In a cotton gin adapted to operate upon previously unginned cotton, the combination with a saw cylinder, of ribs through which the saws project, a roll box in front of said 95 ribs to receive the cotton to be ginned, a rotary impeller in said roll box adapted to turn the roll of cotton therein bringing successive portions of the cotton roll in contact with the projecting portions of the 100 saws, circular disks secured to and turning with said impeller at the ends of said roll box, the said disks fitting in circular recesses in the end walls of said roll box, and means for positively rotating said saw cylinder and impeller at different speeds the driving connections being such as to rotate the impeller at a speed less than the speed of the saws but greater than the speed at which a normal 105 roll of cotton would be rotated by the engagement of the saws.

5. In a cotton gin adapted to operate upon previously unginned cotton the combination with a saw cylinder, of ribs through which the saws project, a roll box in front of said 115 ribs to receive the cotton to be ginned, a rotary impeller in said roll box arranged out of center and on the side next to the saw adapted to turn the roll of cotton therein bringing successive portions of the cotton 120 roll in contact with the projecting portions of the saws and means for positively rotating said saw cylinder and impeller at different speeds the driving connections being such as to rotate the impeller at a speed 125 less than the speed of the saws but greater than the speed at which a normal roll of cotton would be rotated by the engagement of the saws.

6. In a cotton gin adapted to operate upon 130

previously unginned cotton the combination with a saw cylinder, of ribs through which the saws project, a roll box in front of said ribs to receive the cotton to be ginned, a rotary impeller in said roll box at a higher level than said saws and arranged out of center on the side next to said saws adapted to turn the roll of cotton therein bringing successive portions of the cotton roll in contact with the projecting portions of the saws and compressing said roll at the point where it is about to leave the saws and means for positively rotating said saw cylinder and impeller at different speeds the driving connections being such as to rotate the impeller at a speed less than the speed of the saws but greater than the speed at which a normal

roll of cotton would be rotated by the engagement of the saws.

7. In a cotton gin adapted to operate upon previously unginned cotton the combination with a saw cylinder, of ribs through which the saws project, a roll box in front of said ribs to receive the cotton to be ginned, an impeller in said roll box for positively engaging and rotating throughout its length a roll of cotton therein at a peripheral speed greater than that which would be given to a normal roll of cotton by the engagement of the moving saw teeth and for compressing that portion of the roll being engaged by the saws.

In testimony whereof I affix my signature.

SAMUEL J. WAKEFIELD.
